CLAIM

The ornamental design for a vertical semi-hexagonal eyeglass lens with horizontal semi-ovular aperture, as shown and described.

DESCRIPTION

FIG. 1 is a front environmental view of a vertical semi-hexagonal eyeglass lens with horizontal semi-ovular aperture showing my new design;

FIG. 2 is a front perspective view of the vertical semi-hexagonal eyeglass lens with horizontal semi-ovular aperture;

FIG. 3 is a front view thereof;

FIG. 4 is a rear view thereof;

FIG. 5 is a right side view thereof with a left side being a mirror image;

FIG. 6 is a top view thereof; and,

FIG. 7 is a bottom view thereof.

The broken lines are included for illustrative purposes only and form no part of the claimed design.
